WAR GAME APPARATUS

Corliss W. Hall, Dayton, Ohio

Application February 28, 1949, Serial No. 78,785

7 Claims. (Cl. 273—130)

1

This invention relates to a game and particularly to a parlor game embodying both elements of chance and skill.

It is the object of the present invention to provide an attractive parlor game of the type generally known heretofore under the designation of "Salvo," in which the targets may be set up securely on the opposing game boards, with attractive indications of the location of the targets, the shots which are directed towards the opponent's targets and the possible hits scored thereon.

It is a further object of the invention to provide a collapsible game embodying a pair of opposed game boards, which is rugged in construction, economical to produce and attractive in appearance as a result of the utilization of an illuminated interior with colored, light transmitting playing pieces in the form of pegs which transmit light from the interior of the game to the exterior of the game boards while effectively concealing the disposition of the playing pieces on the opposing boards.

The invention is based upon the principle of a game of the type disclosed in the patents to Blau, No. 2,053,598, Heath, No. 2,058,079 and Wupper, No. 2,100,421, in which targets, in the form of different types of battleships, are set up on a playing field by each of two opponents which the other seeks to destroy or incapacitate by directing shots in an effort to first guess the location of the targets by chance and then by skill, once the targets have been struck by one of the directed shots.

It is the object of the present invention to improve upon such games as are known in the prior art by providing game boards each having a plurality of juxtaposed spaces with a plurality of apertures positioned at corresponding points in each of the spaces in order to accommodate playing pegs which may be easily inserted and removed from the apertures rapidly and with certainty. In the preferred embodiment of the invention, one of the apertures in each of the spaces serves to accommodate the pegs for delineating the location of the targets, which are preferably designated as different forms of airships such as a bomber, fighter, scout and cargo ship, and these different ships are laid out on the playing board by differently colored pegs for each type of ship, requiring a plurality of pegs arranged in juxtaposed spaces of the gameboard along either a horizontal, vertical or diagonal line. A second one of the apertures in each of the playing spaces serves to receive the individual

2

pegs designating the shots which are called against the opponent's targets in order that such shots will be called no more than once, and in those instances where such shots strike the opponent's target, these are distinguished from the ineffective shots by the use of a distinctively colored peg. A third aperture in each one of the spaces on the playing board may serve to receive pegs for noting the spaces which are called by the opponent against the player's targets and more particularly the spaces in which hits are scored by the opponent against said target in order to apprise the player of the proximity of the shots scored by the opponent against the targets which are delineated on the player's board.

The provision of light transmitting pegs of plastic material of different colors, coupled with the illumination of the interior of the game, results in one of highly attractive appearance and esthetic appeal.

In order to preclude any possible viewing of the opponent's board through the openings in the boards, each playing board includes a self-sealing flexible layer of material, preferably of sponge rubber, which permits a convenient and rapid insertion and removal of the playing pegs and the retention thereof while they are impaled on the board while blocking off these openings when the playing pegs are removed from the apertures in the respective playing boards.

The invention comprehends a playing board which, in addition to the playing area with apertures therein, has a plurality of apertures for receiving the pegs in their inoperative positions which results in a highly compact game arrangement. When a gameboard of laminated cardboard and flexible sheet rubber is used, all of the apertures may be stamped out in a rapid and single mechanical operation. If desired, additional apertures in scoring boxes may be provided to designate the count of the shots which are made on the opponent's target units as well as the shots which the opponent has scored on the player's targets to obtain a clear summary of the status of the battle.

Other objects and purposes will appear from the detailed description of the invention following hereinafter, taken in conjunction with the accompanying drawings, wherein

Fig. 1 is a perspective view of the game in accordance with the present invention;

Fig. 2 is a vertical longitudinal section through the center of the game unit showing the disposition of the game boards with the light source therebetween;

Fig. 3 is a horizontal sectional view along line 3—3 of Fig. 2;

Fig. 4 is a sectional view along line 4—4 of Fig. 1;

Fig. 5 is an enlarged view of the lower portion of the game board showing the placement of the playing pegs on the board in their inoperative positions; and

Fig. 6 shows a scoring summary which may be incorporated on the face of each of the game boards in a different embodiment of the invention.

As shown in Fig. 1, the game is formed essentially of two oppositely disposed game boards 10 and 10', each of identical construction and identical indicia thereon, in order that the game may be played by two opponents with the game board of each concealed from the view of the other.

Only one game board will be described in detail in view of the identity between the two, and as shown in Fig. 1, the face of the game board 10, which may be formed of cardboard, plastic, wood or any other material, bears a plurality of juxtaposed playing spaces, which, in the illustrated embodiment has been shown in the form of thirty-six squares arranged in six vertical rows designated 1, 2, 3, 4, 5, and 6, and six horizontal rows designated A, B, C, D, E and F. Thus, each square can be readily designated by reference to the vertical numerical and horizontal lettered coordinates. Each one of the squares may be provided with three corresponding spaced apertures in each square for the reception of playing pegs and, as shown in the drawing, one of the apertures may be in the upper left hand corner of the square, the second one may be disposed centrally at the bottom of each square, and a third one of the apertures may be disposed in the upper right hand corner of each square. Different targets are adapted to be located upon the playing field in any desired location, and these targets may be represented by three bomber pegs 11 of yellow color, three fighter pegs 12, which may be of green color, two scout playing pegs 13 of blue color, and two cargo plane pegs 14 of pink color. It is necessary that the pegs of each one of the planes be disposed in juxtaposed squares in either a horizontal, vertical or diagonal direction and it is also necessary that corresponding openings in each one of the squares be used for the reception of the pegs representing the combat targets. As shown in Fig. 1, the upper left hand apertures of the squares may serve to receive the target pegs. Thus, in the illustrated setting in Fig. 1, the bomber is shown located in squares A-1, B-1 and C-1. The fighter pegs 12 are located in squares B-3, B-4 and B-5. The scout plane pegs are shown located in squares E-1 and F-2 and the cargo plan pegs are shown located in squares E-4 and F-3.

Following the setting of the targets by each one of the players, the first player takes three shots on the opponent's target and these are represented by the pegs 15 which may be of clear transparent plastic. As shown in Fig. 1, the player playing the game board 10 has called D-3, C-4 and B-5 against the player playing the game board 10', and as each of these targets is called, a peg is inserted in the corresponding squares located near the center and bottom thereof. The first two shots called by the player 10 were misses, as declared by the opponent, and for that reason pegs 15, of clear

plastic, were inserted in squares D-3 and C-4. However, when the player called B-5, the opponent declared that a hit was made and for that reason a peg 16, of distinctive red color, was inserted in the opening in that square to indicate that some target is disposed in one or more squares in juxtaposed relation to B-5, so that subsequent shots can be directed in that vicinity of the game board in order to incapacitate completely any target plane which may have been disposed by the opponent at that portion of the game board.

It is then the opponent's turn to take three shots against the targets disposed on the board 10 which the opponent notes in corresponding fashion by inserting his pegs 15 or 16 from board 10' in the bottom openings in the respective squares, in a manner similar to the designations above described in connection with the player operating on board 10.

The third aperture in each one of the squares, in this case the apertures in the upper right hand corners of each of the squares, may be used to designate the shots called by the opponent and these are primarily made only when such shots score hits against the player's targets. Thus, one of the shots called by the opponent was B-4 and for that reason a peg 17, which may be of brown color, was inserted in the upper right hand corner of that square to designate that the opponent has scored one hit on the bomber and would most likely call additional shots in that vicinity in order to destroy the target which the opponent estimates to be in that portion of the game board. While it might be desirable in some instances to designate all the shots called by the opponent against the targets on one's board, which would require an additional number of pegs 17, this is not essential.

The game proceeds in the manner described above, each player calling three shots in turn until one has succeeded in bringing down all of the airships of the other. The total number of pegs 15 and 16 combine to make thirty-six possible shots on the playing field of thirty-six squares.

While game boards as described above, embodying apertures and pegs may be conveniently played by opponents in any position as long as each board of each player is concealed from the other, the construction in accordance with the invention provides an attractive and rugged structural unit which effectively disposes the game boards from the view of the opponent while at the same time providing a collapsible assembly having many esthetic features and arresting eye appeal as a result of the illumination of the differently colored pegs by a source of light disposed between the game boards.

As shown in Figs. 2 and 3, the game board 10, which may be of cardboard, is adapted to be formed of laminated construction having a sheet of sponge rubber 25 adjacent thereto which is backed with another layer of cardboard or like material. The apertures 21 in the game board 10 may be punched out at the same time as are the apertures 22 in the backing cardboard 20, which is a very rapid operation. The sheet of sponge rubber 25 is pierced at the same points in order to permit the passage of the shanks of the pegs, but these piercings are self closing when the pegs are removed therefrom so that the openings 22 are not visible from openings 21.

The game board 10' is formed similarly to the game board 10 and the two sheets of apertured cardboard are maintained in integrated condi-

tion with the intermediate sheet of flexible material by means of rivets 23.

As shown in Figs. 2 and 3, the game boards are set up in opposed relation with a base extending therebetween, and a smaller top, to delineate a form of trapezoid in cross-section (Fig. 2). The base portions 26, 26' are separated from a central portion 27 along scoring lines 35 so that the center portion 27 may be folded upwardly in the space between the game boards. The top of the game board is closed by a wall 32 provided with ventilating apertures 33 in the top thereof and walls 34 of flexible material, such as sheet rubber, serve to close off the lateral boundaries between the edges of the game board and the top. A lamp socket 28 is mounted on the intermediate portion 27 for receiving a light bulb 29 which is energized from an electric cord 30 terminating in a plug 31 which may be inserted in any available outlet receptacle. The resulting structure is a substantially closed housing embodying a light source on the interior thereof which serves to illuminate the game and transmit the light from between the game boards to the exterior thereof, resulting in a very pleasing and attractive game.

If desired, the scoring of the individual hits upon the respective targets of the opponent, as well as those of the player, may be kept by the provision of summary scoring boxes as shown in Fig. 6. In such case, additional pegs would be required for insertion in the apertures 36 to designate the hits scored by each player on the respective target of the opponent, as declared by the latter, as well as pegs for apertures 35' to summarize the hits scored by the opponent on the player's targets. Any desired scoring counts may be devised to give the loser partial credit for the damage he has done although the winner first succeeded in destroying all of the target units of the former.

While I have described my invention as embodied in a specific form and as operating in a specific manner for purpose of illustration, it should be understood that I do not limit my invention thereto, since various modifications will suggest themselves to those skilled in the art without departing from the spirit of my invention, the scope of which is set forth in the annexed claims.

I claim:

1. A game board having outlined thereon a plurality of juxtaposed spaces arranged in horizontal and vertical lines, said board having three apertures in each one of said spaces at correspondingly positioned points thereof, a plurality of sets of pegs insertable in said apertures at the three corresponding points thereof, comprising one set of pegs to designate a plurality of combat targets with each target delineated by a predetermined number of pegs at the corresponding point in a series of consecutive spaces along a horizontal, vertical or diagonal line, a second set of pegs insertable at a second corresponding point of said juxtaposed spaces to designate the location of called shots against opponent's targets, and the remaining corresponding apertures in said spaces adapted to receive designations of the shots called by the opponents against the targets set up on said game board.

2. A game board having outlined thereon a plurality of juxtaposed spaces arranged in horizontal and vertical lines, said board having three apertures in each one of said spaces at correspondingly positioned points thereof, a plurality of sets of pegs insertable in said apertures at the

three corresponding points thereof, comprising one set of pegs to designate a plurality of combat targets with each target delineated by a predetermined number of pegs at the corresponding point in a series of consecutive spaces along a horizontal, vertical or diagonal line, with the pegs of each target being distinguishable from those of the other targets, a second set of pegs insertable at a second corresponding point of said juxtaposed spaces to designate the location of called shots against opponent's targets, with said pegs being distinguishable between the shots which have struck the opponent's targets and those which have missed said targets, and a third set of pegs insertable at the third corresponding point of said juxtaposed spaces to designate hits scored by opponent on said first-mentioned combat targets delineated on said game board.

3. A game comprising a pair of independent upstanding game boards disposed oppositely and angularly with respect to each other, each board having a plurality of spaces with apertures therein, and pegs insertable in said apertures by opponents playing on each of said game boards bearing information requiring concealment from each other, each of said game boards embodying a layer of flexible material which is penetrable by said pegs but which otherwise is self-sealing so that said apertures on each game board cannot be seen by the opponent.

4. A game comprising a pair of independent upstanding game boards disposed oppositely and angularly with respect to each other, a foldable base interconnecting the bottoms of said game boards, a lamp socket mounted on said base, a top provided with ventilating openings extending between the upper ends of said game boards, flexible walls extending between the sides of said game boards to form a substantially closed housing for the light source adapted to be mounted in said lamp socket, each board having a plurality of spaces with apertures therein, and differently colored light transmitting pegs insertable in said apertures by opponents playing on each of said game boards bearing information requiring concealment from each other, each of said game boards embodying a layer of flexible elastic material which is penetrable by said pegs but which otherwise is self-sealing so that said apertures on each game board cannot be seen by the opponent.

5. A game as set forth in claim 3 wherein each game board is formed of a pair of sheets of cardboard with an intermediate layer of sponge rubber therebetween and a plurality of apertures on the board for receiving the pegs in their inoperative position in addition to the apertures in the playing spaces.

6. A game board of laminated material having outlined thereon a plurality of juxtaposed spaces arranged in horizontal and vertical lines, said board having a plurality of sets of apertures in each one of said spaces at correspondingly positioned points thereof, a plurality of light transmitting pegs of different colors insertable in said apertures at corresponding points thereof, comprising one set of pegs to designate a plurality of combat targets with each target delineated by a predetermined number of pegs at the corresponding point in a series of consecutive spaces along a horizontal, vertical or diagonal line, and a second set of pegs insertable at a second corresponding point of said juxtaposed spaces to designate the location of called shots against opponents' targets, said game board having a plurality

of apertures for seating said pegs in their inoperative positions, a light source behind said game board, and said game board embodying a layer of flexible elastic material which is penetrable by said pegs but which otherwise is self-sealing to block off the transmission of light from the opposite faces of said board except that passing through said pegs.

7. A game comprising a pair of independent upstanding game boards disposed oppositely and angularly with respect to each other, a foldable base interconnecting the bottoms of said game boards, a lamp socket mounted on said base, a top provided with ventilating openings extending between the upper ends of said game boards, and flexible walls extending between the sides of said game boards to form a substantially closed housing for the light source adapted to be mounted in said lamp socket, each board having outlined thereon a plurality of juxtaposed spaces arranged in horizontal and vertical lines, said board having three apertures in each one of said spaces at correspondingly positioned points thereof, a plurality of sets of differently colored light transmitting pegs insertable in said apertures at the three corresponding points thereof, comprising one set of pegs to designate a plurality of combat targets with each target delineated by a predetermined number of pegs at the corresponding point in a series of consecutive spaces along a horizontal, vertical or diagonal line with the pegs of each target being distinguishable from those of the other targets, a second set of pegs insertable at a second corresponding point of said

5 juxtaposed spaces to designate the location of called shots against opponent's targets, with said pegs being distinguishable between the shots which have struck the opponent's targets and those which have missed said targets, and a third set of pegs insertable at the third corresponding point of said juxtaposed spaces to designate hits scored by opponent on said first-mentioned combat targets delineated on said game board, and said board having a plurality of apertures therein for receiving said differently colored pegs in their inoperative positions preparatory to their placement in their playing positions.
